CLAIM

The ornamental design for a jewelry ring, as shown and described.

DESCRIPTION

FIG. 1 is a front and right side perspective view of a first embodiment of a jewelry ring showing my new design;

FIG. 2 is a rear and left side perspective view thereof;

FIG. 3 is a bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a top, front and right side perspective view of a second embodiment of a jewelry ring showing the new design;

FIG. 10 is a rear and left side perspective view thereof;

FIG. 11 is a bottom perspective view thereof;

FIG. 12 is a front elevational view thereof;

FIG. 13 is a rear elevational view thereof;

FIG. 14 is a left side elevational view thereof;

FIG. 15 is a right side elevational view thereof; and,

FIG. 16 is a top plan view thereof.
